UNITED STATES PATENT OFFICE.

JOHN H. PATTERSON, OF DAYTON, OHIO, ASSIGNOR TO THE NATIONAL CASH REGISTER COMPANY, OF SAME PLACE.

COMBINED ACCOUNT BOOK AND HOLDER.

SPECIFICATION forming part of Letters Patent No. 425,455, dated April 15, 1890.

Application filed June 24, 1889. Serial No. 315,337. (No model.)

To all whom it may concern:

Be it known that I, JOHN H. PATTERSON, a citizen of the United States, residing at Dayton, in the county of Montgomery and State of Ohio, have invented certain new and useful Improvements in Combined Account Books and Holders, of which the following is a full, clear, and exact description, reference being had to the accompanying drawings, forming part of this specification.

The object of my invention is to simplify and lessen the labor of keeping petty accounts in stores where it is the practice for the salesmen or saleswomen to make duplicate itemized sales-slips of all sales, or at least of all credit sales, one of which duplicates is given to the customer with the goods purchased and the other is sent to the book-keeping department to be entered on the proper books. In such establishments it is usually the practice to transfer the items appearing on the sales-slips to the blotter or sales-book in detail, from which they are carried to the various account-books, according to the system of book-keeping employed, being finally entered on the ledger simply as "Mdse." of a certain gross amount on a certain date. It results from this practice that not only does each separate item appearing on the sales-slip have to be transferred to and entered upon at least one book, but when it is desired to render a bill to the customer such book has to be referred to for an explanation of each of the "Mdse." entries appearing on the ledger. I have provided an improved account book and holder for such sales-slips, by the use of which, in the manner hereinafter described, all entries of the separate items of said slips on the sales-book, day-book, or other books employed is rendered entirely unnecessary either for the mere purpose of preserving the items of the account or for reference to them in rendering bills of the same.

The novelty of my invention will be herein set forth, and specifically pointed out in the claims.

In the accompanying drawings, Figure 1 is a perspective view of my improved account book and holder. Fig. 2 is a perspective view of a pad of blank bill-heads to be used in connection therewith.

My improved combined book and holder consists of any suitably-shaped bound and indexed book A, to the leaves B of which are permanently secured in any convenient manner the blank envelopes or pockets C, closed at their sides and bottoms and open at their tops. Extending across and secured to each of these envelopes are two or more rubber bands a, beneath which is inserted the bill-head D, suitably ruled, as indicated, for the entry of the debit and credit items of an account and to have the name of the customer written on its top. Stub-leaves E are bound in with the leaves B to give proper thickness at the binding. When the sales-slips are sent to the book-keeper's desk by the salesmen, each is inserted in its proper envelope C in the book, and the aggregate amount of its items, together with the date and the number of the slip, (if numbered,) are indorsed on the bill-head D, which is detachably held on the outside of said envelope. If at any time the customer makes a payment on account, the amount is entered on the credit side 75 of this bill-head, and thus the entire account is kept there. At the end of the month, or at such other time as it is desired to render the customer a bill, the bill-head D itself is slipped out from under the rubber bands a, 80 the balance struck on it, and it is sent directly to the customer as a bill. The sales-slips in the envelopes, which contain the items of the account, can be taken out and pinned together, or a rubber band put around them, and be 85 put back in the envelope and preserved until the account is paid. In the meantime, if the account with the customer is expected to continue, a fresh bill-head is inserted under the bands a and the customer's name written on 90 it, and as additional credit sales are made to the customer the sales-slips are inserted in the envelope, as before, (being kept separate from the old ones, because the latter are pinned or otherwise held together,) and the 95 aggregate amount of the items on each new slip is entered on the new bill-head D, as in the first instance. In this manner the individual items appearing on the sales-slip, which items are generally quite small and often numerous, are not required to be written but once, and that by the salesman when

the sale is made, so that the book-keeper is relieved of all such labor and the keeping of the account much cheapened and simplified.

It will of course be understood that the loose bill-heads D may be detachably secured to the envelopes C by other means than the rubber bands a—as, for instance, by having their corners inserted in slits in the envelopes or slightly secured thereto with mucilage.

- 10 I am aware that it has heretofore been proposed to keep petty accounts in a manner and by a system similar to that above described in the use of my invention, and I am also aware that there has been designed for that purpose a combined account book and holder in which a series of ruled envelopes were detachably secured to the leaves of the book to hold the sales-slips and to receive the name of the customer and the entry of the 15 amounts of the slips; but in the use of such book, when it was desired to send the customer a bill the items appearing on the face of the envelope had either to be copied off onto a separate bill-head or else the envelope 20 itself had to be detached from the leaf of the book and sent to the customer as a bill. Either practice was objectionable, for in the first case, if the items were copied onto a separate bill-head and sent to the customer, 25 the account could not be continued without detaching the envelope from the book and preserving it and its contents in a separate place until the bill was paid, and in the meantime inserting a new envelope in its place;

and, in the second case, if the envelope itself 35 was detached and sent to the customer, it was not a neat or business-like way in which to present a bill. There was no convenient place left in which to preserve the sales-slips until the bill was paid, unless a new envelope were immediately inserted in the place of the one removed, and every time a bill was rendered or an account closed and a new one opened it involved the loss of the old envelope and the expense of a new one and the trouble of attaching the latter to the book.

By the use of my improvement the bill can be sent to the customer in neat and regular form, the sales-slips be conveniently preserved until the bill is paid, and the account 40 continuously carried on with the old customer or a new one opened with a new customer with the same envelopes originally provided in the book.

Having thus fully described my invention, 45 I claim—

The combination, with the book or holder A, having leaves B and stubs E interposed between said leaves, of the envelopes or pockets C, permanently attached to said leaves, 50 and the loose bill-heads D, detachably secured to said envelopes or pockets, substantially as described.

JOHN H. PATTERSON.
